UNITED STATES PATENT OFFICE

SOLOMON FORMAN, OF NEW YORK, N. Y., ASSIGNOR TO FORMAN BROS. INC., OF BROOKLYN, NEW YORK, A CORPORATION OF NEW YORK

DESIGN FOR A CASSEROLE COVER OR SIMILAR ARTICLE

Application filed July 18, 1929. Serial No. 32,109. Term of patent 3½ years.

To all whom it may concern:

Be it known that I, SOLOMON FORMAN, a citizen of the United States, and a resident of New York, in the county of New York and State of New York, have invented a new, original, and ornamental Design for a Casserole Cover or Similar Article, of which the following is a specification, reference being had to the accompanying drawing, forming part hereof.

In the drawing,—

Fig. 2 is a side elevation of the same.

I claim:

The ornamental design for a casserole cover or similar article as shown and described.

In testimony whereof, I have hereunto set my hand on this this 16th day of July, 1929.

SOLOMON FORMAN.
